US00D915749S

(12) **United States Design Patent** (10) Patent No.: **US D915,749 S**
(45) Date of Patent: **** Apr. 13, 2021**

- (54) **SHOE**
(71) Applicant: **adidas AG**, Herzogenaurach (DE)
(72) Inventor: **Lena Groneck**, Herzogenaurach (DE)
(73) Assignee: **adidas AG**, Herzogenaurach (DE)
(**) Term: **15 Years**
(21) Appl. No.: **29/719,889**
(22) Filed: **Jan. 8, 2020**
